Term of patent 3½ years

(Cl. D91—3)

Fig. 1.

Fig. 2.

Fig. 3.

FIG. 1 is a side elevational view of an aerator showing my new design.

FIG. 2 is a cross sectional view of the aerator taken on line 2—2 looking in the direction of the arrows.

FIG. 3 is a cross sectional view of the aerator taken on line 3—3 looking in the direction of the arrows.

The sides of the aerator not shown are substantially the same in appearance as the sides shown.

The dominant features of my design reside in the portions shown in full lines.

I claim:

The ornamental design for an aerator, as shown and described.
